UNITED STATES PATENT OFFICE.

MICHAEL J. TRACY, OF ST. LOUIS, MISSOURI, ASSIGNOR TO PAULY JAIL BUILDING COMPANY, OF ST. LOUIS, MISSOURI, A CORPORATION OF MISSOURI.

PARTITION IN JAIL CONSTRUCTION AND SPEAKING PANEL THEREFOR.

Application filed June 3, 1925. Serial No. 34,582.

To all whom it may concern:

Be it known that I, MICHAEL J. TRACY, a citizen of the United States, residing at St. Louis, in the State of Missouri, have invented certain new and useful Improvements in Partitions in Jail Construction and Speaking Panels Therefor, of which the following is a specification.

My invention has relation to improvements in jail construction and more particularly to the construction of the partition between the prisoners' exercise corridor and the visitors' corridor, the nature of the invention being better apparent from the detailed description thereof in the specification and as also pointed out in the claims.

The object of the invention is to provide a partition that will be proof against jail delivery but at the same time will permit of conversation therethrough. Heretofore the partition between the prisoners' exercise corridor and the visitors' corridor generally consisted of two screens spaced approximately a foot apart, the purpose of the two screens being to prevent a visitor from passing forbidden objects through the partition to the prisoner. However, even though the screens were made of comparatively small mesh it is common for visitors to pass tools, such as saws, through the interstices of the screen, as well as narcotics and liquor. Of course this is what the builders of jails strive to avoid but with more or less indifferent success.

In the present construction of partitions the disadvantages of the double screen are eliminated by building the partition of tool proof steel except for a certain intermediate portion thereof which is provided with windows of wire glass, the composition of which is such as to defy destruction by ordinary means. Then too, the windows are of such size (approximately 4 x 18 inches) that even though it were possible for the prisoner to destroy the glass thereof the opening would not be sufficiently large to permit egress therethrough. Centrally located with respect to the glass panels is what I choose to term a speaking panel, this speaking panel constituting the principal subject matter of the present invention. The advantages of my improved partition including the speaking panel will be better apparent from a de-

tailed description of the invention in connection with the accompanying drawings, in which—

Figure 1 represents a diagrammatic plan of a conventional jail lay-out; Fig. 2 represents in side elevation a fragment of a partition constructed in accordance with my invention; Fig. 3 is a horizontal cross-section taken on the line 3—3 of Fig. 2; Fig. 4 is an enlarged front elevation of my novel speaking panel; and Fig. 5 is a vertical longitudinal section taken on the line 5—5 of Fig. 4; and Fig. 6 is a horizontal cross-section taken on the line 6—6 of Fig. 4.

Referring to the drawings, and for the instant to the jail lay-out in Fig. 1, C, C, etc. represent prisoners' cells communicating with the prisoners' exercise corridor C'. On the outside of the exercise corridor C' is the jailer's corridor J and at one end of the building is the visitors' corridor V adjacent to both the ends of the jailer's corridor and the end of prisoners' exercise corridor. Between the visitors' corridor and the prisoners' exercise corridor is a partition 1 constructed in accordance with the teachings of my invention and on either side of the partition 1 are booths 2, 2 and 2', 2', the former being for the accommodation of visitors and the latter for the prisoners when engaged in conversation. Since this invention is directed to the construction of the partition 1, the description will now be confined thereto.

The partition 1 is constructed principally of tool proof steel plate and is provided with openings 3 in which are fitted non-frangible glass panels 4, said panels being constructed of wire glass of such composition that it will resist the attacks by ordinary instruments and will not be shattered by blows of such articles as generally come into the hands of inmates. The muntins 5 between the panels 4 are likewise constructed of tool proof steel. In order that conversation may be carried on between the parties on opposite sides of partition 1 I insert what I term a speaking panel in the partition, the same being centrally disposed with respect to the panels 4. This speaking panel comprises a casing 6 composed of tool proof steel, the inner wall 7 and the outer wall 8 thereof each having a large number of small perforations 9. Within the box 6 are a plu-

rality (in the present case, three) of baffle plates 9, 9' and 9'', the baffle plate 9 having three horizontally disposed slots 10 equally spaced and extending from side to side thereof while the baffle plates 9' and 9'' have two horizontally disposed slots 11 and 11' respectively extending from side to side. It will be observed that the slots 11 and 11' are in alinement but said slots are staggered with relation to the slots 10, the effect of which is to prevent the insertion of any slender article through the punched plate and the slots. If the slots 11' were in alinement with slots 10 it would be possible to insert an article diagonally through the slots 10, 11 and 11' which cannot be done by aligning the slots 11, 11' as shown in Fig. 5. It might be possible in the present construction to insert some instrument through slots 10 and 11 but a continued insertion in a straight line of such article would result in its impinging on the baffle 9''. Thus, the present arrangement of the slots in the baffles 9, 9' and 9'' is of great importance as it has been found in practice that this arrangement is the simplest arrangement that will effectively prevent the passing of articles through the speaking box. The perforations in the walls 7 and 8 together with the slots in the panels readily permit of the passage of sound through the speaking box so that a conversation can easily be carried on between parties on opposite sides of the speaking box. At the same time such parties are conversing they may also see each other through the glass panels 4.

From the foregoing description it must be apparent that I have provided a jail partition that while readily permitting of the passage of sound therethrough is at the same time proof against jail delivery and also proof against illicit traffic in forbidden articles therethrough.

While I have described my improved partition construction and speaking panel as being applicable to jails, obviously it may be used with equal advantage in other in-

stitutions of confinement such as reformatories and asylums.

Having described my invention, I claim:—

1. A partition composed principally of tool proof steel plate, a plurality of window panels therein, and a speaking panel in said partition, said speaking panel comprising a casing having perforate walls.

2. A partition for use in jails composed principally of tool proof steel plate, said plate having a speaking panel therein comprising a casing having perforate front and rear walls.

3. A speaking panel adapted for insertion into a partition, said panel comprising a casing having perforate front and rear walls, and a plurality of baffles within the casing.

4. A speaking panel adapted for insertion into a partition, said panel comprising a casing having perforate front and rear walls, and a plurality of slotted baffles in said casing.

5. A speaking panel adapted for insertion into a partition, said panel comprising a casing having perforate front and rear tool-proof steel walls, and a plurality of baffles within the casing.

6. A speaking panel adapted for insertion into a partition, said panel comprising a casing having perforate front and rear walls, a plurality of slotted baffles in said casing, the slots of one baffle being staggered with relation to the slots of the next adjacent baffle.

7. A speaking panel adapted for insertion into a partition, said panel comprising a casing having perforate front and rear walls, a plurality of slotted baffles disposed across the inside of said casing, the slots of two adjacent panels being disposed in alignment, and the slots of the next adjacent baffle being staggered with relation to said aligning slots.

In testimony whereof I hereunto affix my signature.

MICHAEL J. TRACY.
